CLAIM

The ornamental design for a plate stand, as shown and described.

DESCRIPTION

FIG. 1 is a front perspective view of a plate stand showing our new design;

FIG. 2 is a top plan view thereof;

FIG. 3 is a front elevational view thereof;

FIG. 4 is a right side elevational view thereof, the left side elevational view thereof being a mirror image;

FIG. 5 is a rear elevational view thereof; and

FIG. 6 is a bottom plan view thereof.
